CLAIM

The ornamental design for turbine mixing device for
liquids or the like, as shown and described.

DESCRIPTION

FIG. 1 is a top plan view of a turbine mixing device for
liquids or the like, showing my new design;

FIG. 2 is a side elevational view thereof, taken in the
direction of arrow 2 in FIG. 1;

FIG. 3 is a bottom plan view thereof;

FIG. 4 is a side elevational view thereof, taken in the
direction of arrow 4 in FIG. 3; and,

FIG. 5 is a cross-sectional view thereof, taken on line
5—5 of FIG. 1.

FIG. 1

FIG. 4

FIG. 2

FIG. 3

FIG. 5
